Primary Examiner — Leanne Was-Englehart(57) **CLAIM**

The ornamental design for a probe for food thermometer, as shown and described.

DESCRIPTION

FIG. 1 is a perspective view of a probe for food thermometer showing my new design;

FIG. 2 is a front elevation view thereof;

FIG. 3 is a back elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged view thereof taken from FIG. 1.

The broken line circle in FIGS. 1 & 8 depicts the limits of the enlarged view.
